UNITED STATES PATENT OFFICE.

GEORGE W. BOTHWELL, OF ONTARIO, CALIFORNIA.

FEED MEANS FOR OIL-BURNING APPARATUS.

1,116,790.

Specification of Letters Patent. Patented Nov. 10, 1914.

Application filed June 9, 1913. Serial No. 772,599.

To all whom it may concern:

Be it known that I, GEORGE W. BOTHWELL, a citizen of the United States, residing at Ontario, in the county of San Bernardino and State of California, have invented a new and useful Feed Means for Oil-Burning Apparatus, of which the following is a specification.

This invention relates to an apparatus for burning oil for heating orchards or for other purposes, and the main object of the invention is to provide an apparatus which will require the minimum of care or oversight during its operation.

The invention relates to oil burning apparatus of the class wherein oil in an airtight tank is supplied gradually by allowing air to enter the tank to displace the oil, on the principle of a fountain feed. In such fountain feed apparatus a quantity of oil is allowed to escape in starting before sufficient vacuum is obtained in the tank to sustain the column of oil in the tank, and one object of the invention in this connection is to provide means for collecting and holding the oil escaping in this manner and supplying it gradually to the burner.

A further object of the invention is to provide convenient means whereby the apparatus may be regulated for effective operation and the supply of oil may then be turned on and off without disturbing the regulation.

Another object of the invention is to provide for cutting off the connection between the tank and the fountain feed means when the burner is not being used, so as to maintain a condition of vacuum in the supply tank.

Other objects of the invention will appear hereinafter.

The accompanying drawings illustrate an embodiment of my invention, and referring thereto:

Figure 1 is a vertical section of the apparatus, the supply tank being shown partly in elevation. Fig. 2 is a side elevation of the feed controlling device. Fig. 3 is a plan view of the feed devices, portions of the tank being shown in section.

1 designates a supply tank having a closure 2 at the top which is adapted to tightly close the tank during operation, and is only removed for the filling of the tank. Said tank 1 is preferably supported on a reservoir 3, formed as an open topped pan

adapted to fit within a flange 4, extending downwardly from the tank 1. An outlet pipe 5 leads from the lower part of tank 1 to a valve 6 controlling communication from the outlet pipe 5 to a tee 7, one branch of which is connected through a regulating valve 8 to a fitting 9 having an outlet connection 10 to the reservoir 3. A siphon tube 11 extends upwardly from the tee 7 from a point below the top of the reservoir and over and downwardly into the fitting 9, being sufficiently smaller than the fitting 9 to permit air to enter fitting 9 around the siphon tube 11.

Reservoir 3 has an outlet pipe 12 communicating with any suitable heater, for example, with a heater of the type shown in my application, Serial No. 763,438, filed April 24, 1913, comprising a heater casing 14 having a stack 15 and provided with a vaporizing tube 16 within the casing and an outlet 17 for directing a jet of vapor into the casing, said casing having an air inlet 18 through which extends the supply pipe 19 for the heater. Said supply pipe 19 communicates through a seal consisting of a downward and upward bend 20 in the pipe 12 aforesaid, the outer end of said pipe 12 being connected to a tee 22 which is connected to the supply pipe 19 for the heater, and a stand pipe 23 being connected to said tee and extending upwardly and being open at its upper end to serve as a vent as described in my said application. In place of this form of heater, however, any other form of heater may be used which is adapted to operate with a small pressure of oil. In order to facilitate disconnection of the heater from the supply tank, pipe 12 is preferably connected to the reservoir 3 by a coupling consisting of a screw sleeve 25 having right and left screw threads engaging respectively with a screw thread on the pipe 12 and with a screw thread on a nipple 26 screwing into the side of the reservoir 3.

The operation of this form of my invention is as follows: Tank 1 is filled with oil, the closure 2 being removed for that purpose and then tightly replaced, so as to prevent air from entering the tank during the operation. When it is desired to use the burner, the valve 6 is opened wide and the valve 8 having been previously opened to proper extent for operation of the burner, oil flows down through the fittings 5, 6, 7, 8 and 9 into the reservoir 3, the line of fittings aforesaid

being inclined as shown in Fig. 2 to facilitate passage of the oil in this manner. Any excess of oil in starting, due to a larger opening of the valve 6 than of the valve 8 is carried off through the tube 11 and discharged into the fitting 9, passing thence into the reservoir 3. Said reservoir is of sufficient capacity to hold all of the oil which escapes during the production of a vacuum in the upper part of tank 1, sufficient to sustain the remaining column of oil in the tank and the oil thus flowing into reservoir 3 flows gradually through the outlet pipe 12 to the burner in the heater. The regulating valve 8 is adjusted so that when the vacuum has once been established, the said valve will carry off the oil flowing through the main valve, but will retain in the tee 7 enough oil to cover the lower part of the outlet of the shut off valve 6 so that the device acts as a fountain feed, the air for displacing the air in the supply tank 1, entering through the tube 11 and passing up through the valve 6 whenever the oil in the reservoir 3 and fittings 7, 8 and 9 falls below the level of the inlet of tube 11 into tee 7, such inlet being indicated by a dotted line *z* in Fig. 2. When this occurs a small quantity of the oil is discharged, enough to accumulate in and fill the tee 7 sufficiently to close this opening of the valve 6 momentarily until the regulating valve 8 has time to draw off enough oil to again lower the level of the oil as above stated. Vaporizing pipe 16 in the heater has a bend 16' rising to sufficient height to retain the oil in the burner at the level of line *z* when the burner is not in operation.

An important feature of the invention is the provision of the shut off valve 6 between the tank and the air inlet for the fountain feed. I have found that in applying a fountain feed to a tank of this charac-

ter especially when the same is used in the open air in connection with orchard heaters, the fluctuations of temperature cause sufficient dilatation and contraction of the gases in the upper part of the tank 1 to interfere with the preservation of an effective vacuum in the upper part of said tank, the vacuum being reduced in the expansion of the gas and not being fully restored in contraction, due presumably to gradual evaporation of gas into the space above the liquid in the tank by reason of the low pressure therein and the heating of the liquid and this gas not being fully absorbed when the liquid again cools. By closing the valve 6 tightly when the burner is not in use, I am enabled to retain a condition of vacuum indefinitely in the tank 1, so that when the valve 6 is again opened, the burner starts to operate immediately in normal manner without any sudden outrush of oil due to lack of vacuum in the tank.

What I claim is:

In an oil burning apparatus, a feed means comprising a tank, a reservoir below the tank, an outlet connection leading from said tank to said reservoir and provided with two valves, and having an air inlet opening in its top between one of said valves and said reservoir, and an air inlet tube extending above said air inlet opening and communicating with said outlet connection between said valves, at a point below the top of the reservoir.

In testimony whereof, I have hereunto set my hand at Los Angeles, California this 29th day of May, 1913.

GEORGE W. BOTHWELL.

In presence of—

ARTHUR P. KNIGHT,
MARTHA M. LANGE.
